UNITED STATES PATENT OFFICE.

CONRAD J. KORTZ, OF CLEVELAND, OHIO.

BILL HOOK.

Application filed September 27, 1926. Serial No. 137,975.

My invention relates to an improvement in bill hooks of the kind and type shown and described in Letters Patent of the United States, granted to me, October 5, 1909. Number 935,997. The present device embodies certain features found in my former structure but it also embodies new features of construction which yield improved results and advantages, all as hereinafter shown and described and more particularly pointed out in the claims.

In the accompanying drawings, Fig. 1 is a perspective view of the bill hook showing the hook pulled down as in use. Fig. 2 is a rear view of the device showing the hook raised and folded flat against the back of the card or main supporting body. Fig. 3 is a side elevation of the bill hook opened as in Fig. 1. Fig. 4 is a rear view and section, enlarged, of the locking plate on line 4—4 of Fig. 6, and Fig. 5 is a sectional view vertically of the card and plate on line 5—5 of Fig. 4. Fig. 6 is a sectional view of the card and plate on center line 6—6 of Fig. 4. Figs. 7 and 8, are transverse sections of the card and plate on lines 7—7 and 8—8, respectively of Fig. 4.

The present bill hook comprises a flat card 2 having a metal hook 3 secured in slidable and foldable connection therewith as in my former device. The card usually displays advertising matter on its front face, and the construction and cost of production thereof is a factor because such bill hooks are usually distributed free for their advertising value. Distribution proceeds mainly through the mails where the device is subject to stamping and crushing pressure. Upon receipt the user suspends the device from a nail, using an opening 4 in the upper part of the card for that purpose. Wire hook member 3 has a straight shank 5 which is bent at right angles at its upper end, and this angular extremity 6 is adapted to enter the large end of a flaring grooved rib 7 formed in a metal holding plate 8 which is secured to card 2 by a pair of metal eyelets 9. Shank 5 extends through the groove or channel at the inner side of rib 7 and protrudes through the smaller end thereof where a snug sliding fit is established therefor. When the hook member is drawn down its angular extremity 6 engages the sloping wall of the grooved rib 7 with wedging and locking effect. In this position the hook

member cannot turn or rotate on the axis of its shank, and because card 2 is made of stiff paper or the like it will flex or yield to some extent and bind the shank where engaged with the card when bent extremity 6 is wedged in grooved rib 7. If the pull on hook member 3 is excessive or overdone the paper card may be disrupted or torn at or between the fastening eyelets, or a wobbly connection may be produced. I therefore provide a series of indentations 10—10 at spaced intervals in the opposite sides of grooved rib 7 to resist such extreme pulls after wedging at extremity 6 takes place. These indentations 10—10 are also spaced apart sufficiently to form a locking recess for the bent part 6 so that the hook member may not be easily pushed in opposite directions after it has been withdrawn for use. However, the indentations are shallow and rounded and the wire itself is round, so that the engaging surfaces may ride over one another when sufficient pressure is applied to overcome the spring resistance of the side walls of grooved rib 7. A plurality of spaced indentations 10—10 is also preferred to permit the use of hook members having angular lugs or extremities of varying length. Accuracy in production is therefore unnecessary and production is cheapened. Effective locking is nevertheless obtained, because if the angular lug or bent part 6 is too short to wedge against the sloping wall of the grooved rib when drawn between two parallel sets of indentations 10—10 the hook member may be drawn out an additional distance until wedging is effected with the sloping wall and locking engagement is obtained between the next set of indentations.

Plate 8 is rigidly secured to card 2 by eyelets 9 which are located outside of but relatively near the side walls of center rib 7, and two straight ribs 11—11 are stamped in the plate outside of these riveting or eyelet places. Ribs 11 extend vertically of the plate and are relatively as high as the highest part of center rib 7 to protect this center rib from being crushed or distorted in transmitting the device through the mails. These additional ribs also re-enforce plate 8 and protect the union of the plate with the card at eyelets 9. Furthermore, when the card is suspended from a nail upon a wall the outer ribs form a stable rest for the card against

the wall and the device will not rock in affixing bills or other matter to the hook. To further stabilize the card the side ribs 10-10 diverge from center rib 7 at the bottom edge of the plate where contact usually takes place with the wall.

What I claim, is:

1. A bill hook comprising a card, a plate having a wedge-shaped channel and indentations in the side walls of said channel, and a hook member having a shank with a bent extremity adapted to be wedged within said channel and held in locked engagement with said indentations.
- 15 2. A bill hook comprising a card having a metallic plate affixed thereto, said plate having a grooved rib with a sloping back, and the side walls of said rib having a plurality of parallel indentations at spaced intervals, and a hook member having a shank within said grooved rib, said shank having an angular extremity, adapted to have wedging engagement with said sloping back and

locking engagement with said parallel indentations.

25 3. A bill hook comprising a card, a plate having an inclined grooved rib centrally thereof and ribs at each side of said central rib, and a hook member having a shank with a bent end adapted to enter and wedge within said grooved rib.

4. A bill hook comprising a card, a plate having a series of grooved ribs and a hook member having a shank slidably and rotatably secured within one of said grooved ribs.

35 5. A bill hook comprising a perforated card, a plate having a central grooved rib and other ribs spaced apart therefrom, means located between said ribs for fastening said plate to said card, and a hook member having a shank slidably and rotatably mounted within said central rib.

In testimony whereof I affix my signature.

CONRAD J. KORTZ.
